UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

REMOVABLE BOGIE FOR TRAILERS, GUN-CARRIAGES, AND OTHER APPARATUS.

1,340,416.

Specification of Letters Patent. Patented May 18, 1920.

Original application filed July 30, 1917, Serial No. 183,595. Divided and this application filed June 16, 1919. Serial No. 304,646.

To all whom it may concern:

Be it known that I, EUGÈNE SCHNEIDER, a citizen of the Republic of France, and a resident of Paris, France, have invented a new and useful Improvement in Removable Bogies for Trailers, Gun-Carriages, and other Apparatus, which invention is fully set forth in the following specification.

In my application Serial No. 183,595, filed July 30, 1917, for improvement in bogies for trailers, gun carriages and the like, of which the present application is a division, I have described a bogie construction capable of being adapted to any desired carriage fram-

ing, such as a trailer or gun carriage the variable number of bogies constituting as many elastic suspension devices.

The characteristic feature of the improved bogies is that the bogie axle is connected at its center by a ball-and-socket joint or a horizontal pin to a member constituting the lower abutment, and it may be also the guide, for an elastic suspension, the upper abutment of which is constituted by one of the essential elements of a screw-jack or like device, which is pivoted about a vertical axis by means of the support of the other element of the screw-jack or by the actual frame of the screw-jack in the carriage framing.

This arrangement is such that, on operating the screw-jacks in one direction, the carriage framing may be lowered to rest on the ground in firing position and by continuing the operation the bogies may be lifted off the ground. By reversing the operation, the bogies may be lowered to the ground and by continuing the operation the framing may be lifted into traveling position off the ground. The bearing of the wheels upon the ground is assured whatever the contour of the surface during travel.

In order that the invention may be more readily understood, reference is had to the accompanying drawings which show one constructional form of the invention.

Figure 1 is a front elevational view, partly in section, showing a bogie construction embodying my improvements.

Figs. 2 and 3 are views similar to Fig. 1 showing the parts in different positions.

Fig. 4 is a cross-sectional detail view on the line 4—4 of Fig. 1.

Referring to the drawings, A, A are the

wheels of a bogie mounted on the ends of an axle B. I is a part of the carriage framing on which is mounted a supporting collar M comprising an element fast to the carriage framing and a complementary element adapted to be hinged to the fixed element by pins m. The collar is adapted to revolubly receive a screw-jack casing G by removing one of the pins m and opening the hinged element of the collar. K is a threaded element of a screw-jack revolubly mounted in the top of the casing G and is provided with a polygonal head for receiving a wrench handle L.

E is an elastic suspension device preferably consisting of a pile of Belleville washers which are confined between a nut F' of the screw-jack and the bottom d of a socket or barrel D which latter is adapted to slide in screw-jack casing G. The lower end of the wall of barrel D is extended in the form of two cheeks D' (Fig. 1) which straddle the axle B and are pivotally connected therewith by a pin C.

In order to limit the pivotal movements of the axle B there is provided a member D² adapted to be screwed or fixed to the socket or barrel D or simply held between the axle and cheeks D'. For a like purpose a collar D³ may be secured on the ends of the cheeks D'.

Rotational movement of the nut F is prevented by a rib F' thereon guided in a slot D⁴ in socket D.

Assuming the parts of the screw-jack bogie are in the position shown in Fig. 1, the framing I can be raised or lowered relatively to the ground within determined limits.

For this purpose it is merely necessary to operate the screw member K by means of lever L. According to the direction of movement of this lever the framing will be caused to rise or to descend. In the latter case the gun carriage to which the screw-jack bogies are pivoted can be lowered to the position shown in Fig. 2 so as to bear upon the ground. Then by continuing to operate the lever L nut F rises on threaded member K against inner collar d² thereby lifting barrel D and with the latter wheels A into a position off the ground as shown in Fig. 3.

By a reverse rotation of lever L the wheels A may be lowered to the ground and fram-

ing I elevated into transporting position off the ground.

What is claimed is:

1. In a bogie for supporting a trailer, gun carriage or other vehicle, the combination of a wheeled axle, a spring barrel pivotally mounted on said axle, a vehicle frame, a tubular member revolvably mounted thereon and adapted to receive said barrel, a threaded rod revolvably supported in said tubular member and provided with a nut movable into lifting engagement with said barrel and a suspension spring in said barrel having said nut as one abutment and the end of said barrel as the opposite abutment.
2. In a bogie for supporting a trailer, gun carriage or other vehicle, the combination of a wheeled axle, a spring barrel pivotally

mounted thereon, a vehicle frame, a tubular member revolvably mounted thereon and 20
adapted to receive said barrel, a threaded rod mounted to revolve in said tubular member and held thereon against longitudinal movement, said rod being provided with a nut having a splined connection with said 25
barrel and movable into lifting engagement with said barrel and a suspension spring in
said barrel having said nut as one abutment and the end of said barrel as the opposite
abutment.

In testimony whereof I have signed this specification.

EUGÈNE SCHNEIDER.
